UNITED STATES PATENT OFFICE.

GUSTAV DARMANN, OF WALD, GERMANY.

DESIGN FOR A PADLOCK-CASE.

SPECIFICATION forming part of Design No. 33,194, dated September 11, 1900.

Application filed May 28, 1900. Serial No. 18,333. Term of patent 3 years.

To all whom it may concern:

Be it known that I, GUSTAV DARMANN, a subject of His Majesty the Emperor of Germany, residing at Wald, in the Province of Rhenish Prussia, Germany, have invented and produced a new and original Design for a Padlock-Case, of which the following is a specification, reference being had to the accompanying drawings, forming part thereof.

Figure 1 is a plan view of a padlock, showing my design. Fig. 2 is a side view of Fig. 1.

As shown in the drawings, the leading or material feature of my design consists in the configuration of the base and top plate of a padlock-case, which is formed according to the figure of an elephant. The body of the creature is represented by the plates *a*. In

one of the plates is shown a keyhole. From the plates *a* extend to the left side short flaps *b* *b'*, forming the legs of the elephant, its trunk being represented by the shackle *c*, which is guided between the two flaps *a'*, that extend from the plates *a* and form the head of the creature the eye of which is constructed by the rivet of the shackle. 25

Having described my invention, what I claim as new, and desire to secure by Letters Patent, is—

The design for a padlock-case as herein shown and described.

GUSTAV DARMANN.
